J. AUGUSTUS LYNCH AND REUBEN K. HUNTOON, OF BOSTON, MASSACHUSETTS.

Letters Patent No. 82,332, dated September 22, 1868.

IMPROVEMENT IN GOVERNORS FOR STEAM-ENGINES

The Schedule referred to in these Letters Patent and making part of the same.

TO ALL PERSONS TO WHOM THESE PRESENTS MAY COME:

Be it known that we, J. AUGUSTUS LYNCH and REUBEN K. HUNTOON, of Boston, in the county of Suffolk, and State of Massachusetts, have made a new and useful invention having reference to Governors for Steam-Engines; and we do hereby declare the same to be fully described in the following specification and represented in the accompanying drawings, of which—

Figure 1 denotes a top view,

Figure 2 a front elevation, and

Figure 3 a longitudinal section of a governor provided with our invention.

Figure 4 is a vertical section of its relay or reinforcer or small auxiliary steam-engine, for operating the throttle or valve of the induction-pipe of the main engine.

Figure 5 is a horizontal section of the relay-cylinder, its steam-valve and chest.

Figure 6 is a vertical and longitudinal section of the mechanism which, in conjunction with the relay-engine, is employed for effecting the stoppage of the main engine or the closing of the throttle-valve of the induction-pipe thereof, in case of the breakage of the belt used for driving or revolving the actuating-pulley of the propeller of the governor.

The said governor, to which our present invention is represented as applied, is, in its essential elements, substantially like that described in Letters Patent, No. 71,015, dated November 19, A. D. 1867, and issued to ourselves.

The throttle or steam-valve we employ in the induction-pipe is also like that shown in the drawing and described in the specification of the said patent.

This valve is exhibited at S as fixed to a shaft, R, and arranged within a chest or case, B, above which is the close cylindrical vessel, A, of the governor. An arm, C, extends from the junction of the valve-chest B and the foot of the case A, and serves to support the relay-engine cylinder A', which extends downward therefrom, in manner as represented. An arm, Q, projects from the valve-shaft R, and is so jointed to the lower end of the piston-rod B' of the cylinder A', as to be moved up or down thereby, by the vertical movements of the piston-rod B'.

Before proceeding further with the explanation of the addition we have made to the governor and the throttle-valve, we will explain in a few words the governor.

A horizontal shaft, F, supporting a screw-propeller, G, is, with such propeller, arranged within the case A, in manner as represented. The shaft F extends from the said case through a supporting-partition, H, and into another vessel, I, which is fixed to the vessel A, and communicates therewith through one or more holes, α α , made in the said partition. The shaft is supported in and by the partition, and in and by a tubular bearing, b, at the end of the cylinder A. Furthermore, there is within the propeller-case, and fixed to the inner surface, a series of ribs, c c c, the office of which is well understood.

K is a long gear, fixed on the shaft of the propeller, and engages with a short pinion, K', fixed on a driving-shaft, L, arranged in the vessel I, and so as to project therefrom, as represented. An endless belt, from a pulley driven by the main engine, is to transmit rotary motion to a pulley, f, fixed on and to the shaft L. That end of the shaft F which is within the vessel I, abuts against an arm, M, extending down into the vessel, and from a shaft, N, arranged transversely thereof and over the said vessel. The shaft N goes through a hollow head or extension, O, raised on the end opening into said vessel I. An arm, P, extending from one end of the shaft N, engages, by means of a connecting-rod, T, with an arm, D', fixed on the shaft E' of the rotary valve F' of the small relay-engine steam-chest G'.

The valve F' is the frustum of a cone, arranged within a corresponding tubular case or seat-tube, H', which extends through and is arranged in the steam-chest G', in manner as represented.

Within the steam chest G', and arranged about the tube H', are two chambers, c' d'. A pipe, e', to lead

steam from the boiler of the engine, opens into the chamber c^1 . A pipe, f' , leading out of the chamber d^1 , is the steam-eduction pipe. It has a stop-cock, g' , arranged in it. This stop-cock is a useful auxiliary, as, by means of it, we can regulate the escape of steam from the exhaust of the relay-cylinder, such being a matter of much importance.

The passages leading from the valve-seat or case H' to the two ends of the steam-space of the cylinder A' are shown at a^1 and b^1 . From each of the passages a^1 b^1 holes (as shown at h' or i') are led through the side of the case H' , they being arranged with respect to each other and at equal distances apart therein, in manner as shown in Figure 7, which is an inner side view of the part H' . There are two other such series, k' l' , of holes, leading through the case H' , and into the two chambers c^1 d^1 , they being shown in Figures 8 and 10, one of which is a top and the other a bottom view of the part H' . They are also shown in Figure 9.

As the valve F' is to vibrate only in a small arc of a circle, the passages through the valve should be properly arranged for leading the steam from the chamber c^1 alternately into opposite ends of the cylinder A' , and so as to exhaust from each of such ends at the proper time into the chamber d^1 .

The arrangement of these passages is shown on an enlarged scale in fig. 9, one being indicated by the black lines, another by the red lines, and the other two by the yellow and blue lines therein.

When the propeller is at the middle of its range of motion, the arm D' should be horizontal, or in such a position as to cause steam to be shut off from flowage into either end of the "relay-cylinder." Should the speed of the propeller be increased, so as to cause it to advance, the arm D' will be lifted, and thereby cause steam to be let into the relay-cylinder, to cause its piston to move in a direction to close more or less the throttle or main valve, and thus diminish the supply of steam to the main engine. On a retreat of the propeller, caused by any slackening of the speed of the main engine, the relay-engine piston will be worked in the opposite direction, so as to cause the main or throttle-valve to open wider, and let more steam pass to the main engine-cylinder.

Thus it will be seen that the object of the relay-engine is to supply an additional means of operating the main valve, and thereby relieve the governor from directly operating such valve, in the manner in which it does, when applied thereto by a connecting-rod leading directly from the arm of the governor to that of the valve. Our addition of the relay-engine renders the governor and the main valve much more sensitive and certain in their operations.

The addition of the relay or reinforcing-engine to my governor, and the main valve or throttle of the induction-pipe, is to such what the relay-magnet and battery are to the main circuit of an electro-magnetic telegraph line, for, by means of the relay-engine or reinforcer, we work the main valve, and thus save the governor the great duty thereof, it being used merely to work the valve of the relay-engine. The advantage of this will be easily seen by persons skilled in steam-engines.

The reverse motion of the valve of the relay-engine is effected by a weight, W , placed on an arm, K^1 , extended from the shaft N , in manner as represented.

We combine with the said shaft, arm, and weight, a mechanism for effecting the sudden closing of the throttle or main valve, S , in case of breakage of the driving-belt of the propeller.

This mechanism may be thus described. The shaft N has another or shorter arm, L' , extended from it, in a direction opposite to that of the arm K^1 , and to the outer extremity of the arm L' one end of a chain, N' , is attached, the other end of such chain being fixed to the weight W . A hole is made laterally through the weight, to allow such weight to receive the arm K^1 through it, and to slide on such arm lengthwise of it. There is placed within the weight and its passage a small spring-latch or bolt, m , whose stem projects through the weight. This latch enters one of a series of notches made in the upper edge of the arm K^1 , the same serving to hold the weight at any desirable distance from the axis of the shaft N .

The arm K^1 is slotted or forked, and receives in the slot a slide, n , (see fig. 6,) which is a longitudinal section of the arm and its adjacent operative parts. The slide n has two slots, o o , made in it obliquely. Pins p go through the arm and these slots, and serve to support the slide within the arm. Furthermore, the inner end of the slide n is hinged to a rod, q , which has a spring, r , applied to it and in the arm K^1 , the spring operating to move the rod q and the slide endwise. A catch-lever, s , arranged in the arm K^1 , in manner as shown, and provided with an operative-spring, t , fixed to the arm, hooks into a notch, u , of the slider, when the slider is forced back to its rearmost position, that is to say, so as to bring a shoulder, v , on the slide against the end of the catch. A stud, w , extends down from the lever-catch.

On a journal, x , projecting from a stationary bracket, y , (shown in fig. 1,) and encompassing the shaft N , is an adjustable arm, z , which turns around as well as slides lengthwise on the journal, and is fixed thereto by a clamp-screw, a^2 . This arm has a spring, b^2 , arranged on it, as shown in fig. 6. There is also within the arm and the spring a bolt, c^2 , so applied to the arm as to be capable of being moved lengthwise therein. A latch, d^2 , to enter a groove, e^2 , in the bolt, serves to hold the bolt in its highest position. When the bolt is in its lowest position, a shoulder, f^2 , of it rests on the bottom of the spring-socket.

When the bolt is in this latter position, it will be out of reach of the stud w , in case the arm K^1 should drop on top of the spring b^2 . When, however, the bolt is in its highest position, and the driving-belt breaks, the speed of the propeller will slacken at once or cease to move, and such propeller, by the weight on the arm, will be forced backward. The arm in falling will cause the stud w to descend upon the top of the bolt c^2 , and as a consequence the lever-catch s will be disengaged from the slide n . The said slide will next be shot forward by the rod q and spring r . In going forward, it will rise and force the weight-catch m out of its notch of the arm K^1 . The weight will next be launched off the arm, and in falling will, by means of the chain N' , pull on the auxiliary arm L' , and thereby suddenly revolve the shaft N , and bring the valve of the relay or reinforcing-engine into a position to cause the piston of such engine to at once effect the closing of the throttle or main valve S .

In case the relay or reinforcing-engine is not employed, the main valve S will be worked directly by the connecting-rod T, being jointed to the arm of the shaft of the said main valve.

The spring b^2 serves to prevent stoppage of the engine when the bolt c^2 is down, and any large increase of duty is suddenly thrown upon the engine, for, were it not for the spring, the lever-catch s, during a sudden depression of the arm K¹, would be liable to be disengaged from the slide n, and this by the concussion of the arm K¹ on the adjustable arm z. The spring prevents such concussion and its consequences.

We claim the combination of the hydraulic governor and a mechanism, substantially as explained, for effecting the closing of the main valve of the engine, in case of breakage of the driving-belt of the governor, such mechanism consisting principally or in substance, not merely of the auxiliary arm L', the catch m, and chain N', but also of the slide or disengager n, the spring r, lever-catch s, and the arm z, provided with the bolt c^2 , or such bolt and the spring b^2 , the whole being applied to the said arm K¹, the governor-case, and the weight W, substantially in manner and so as to operate as specified.

We also claim the combination of the hydraulic governor and the relay or reinforcing-engine applied to the main valve S of the induction-pipe of a steam-engine, as set forth, with the described mechanism for effecting the closing of the said main valve in case of breakage of the driving-belt of the governor.

J. AUGUSTUS LYNCH,
REUBEN K. HUNTOON.
